UNITED STATES PATENT OFFICE.

ROBERT H. PETERS, OF BUFFALO, NEW YORK.

MATERNITY-SKIRT.

No. 873,167.

Specification of Letters Patent.

Patented Dec. 10, 1907.

Application filed March 19, 1906. Serial No. 306,704.

To all whom it may concern:

Be it known that I, ROBERT H. PETERS, a citizen of the United States, and resident of Buffalo, in the county of Erie, and in the 5 State of New York, have invented a new and useful Improvement in Maternity-Skirts, of which the following is a specification.

This invention relates to a maternity skirt. Heretofore skirts of this character 10 have been provided with a draw string so that they could be adjusted to the variation in the waist measurement and they have also been furnished with rubber or tape lacing in the waistband for this purpose. These 15 forms of skirts are objectionable because they are bulky and make the wearer look larger and more conspicuous, and they do not contain any provision for correcting the raising or tipping up of the skirt in front. 20 The object of this invention is the production of a skirt of this character which contains no draw string or lacing and which can be readily adjusted to suit the varying conditions of the wearer for maintaining the 25 draping of the proper height at the front without requiring ripping or basting.

In the accompanying drawings consisting of two sheets:—Figure 1 is a side elevation of a maternity skirt embodying my invention. Fig. 2 is a fragmentary perspective view of the same looking from the rear. Fig. 3 is a horizontal section in line 3—3, 30 Fig. 4. Fig. 4 is a fragmentary vertical section, taken in line 4—4, Fig. 3. Fig. 5 is a 35 fragmentary vertical section, on an enlarged scale, of one of the plait holding clasps. Fig. 6 is a fragmentary horizontal section of the clasp which connects the clamping members of the belt.

40 Similar letters of reference indicate corresponding parts throughout the several views.

A represents the body of the skirt which is made comparatively full at the top so as to permit of enlarging or reducing the size of 45 the waist to suit the condition of the wearer.

At its upper edge the skirt body is provided with a waist band *a* which extends about one half way around the rear or back part thereof. The edges of the placket, *b* in 50 the rear or back part of the skirt may be connected by any suitable fastening, a hook and eye *c* being shown for this purpose in the drawings. The surplus parts of the skirt on

opposite sides of the placket are folded into two plaits *D* which extend forwardly in opposite directions and lie against the inner side of the skirt. Each of these plaits is held in place by means of clasps or fasteners which may be of any suitable construction. Each of these clasps preferably has a *U* shaped body *e* which receives the upper edge 55 of the waist band *a* of the plaited and unplaited part of the skirt, two jaws *f* arranged on the inner sides of the body and an elbow lever *g* pivoted on one side of the body and operating to move one of said jaws toward 60 its companion jaw and grip the fabric between the same, as shown in Fig. 5. Two of such fasteners are preferably employed for each plait the same being located at or near 65 opposite ends thereof, as shown in Figs. 2 and 3. The front side or part of the skirt is provided above the waist line with an upward extension or flap *H* the unused portion 70 of which is adapted to be folded downwardly 75 against the inner side of the skirt. This flap is held at the waist line between the inner and outer sections or members *i*, *i'* of a clamping belt or holder. The members of the clamping belt are preferably crescent 80 shaped so as to pass around the front part of the skirt body and are constructed of spring steel or other elastic material which is covered with a suitable fabric to match the material of the skirt. 85

The corresponding ends of the clamping belt members are connected with each other and with the adjacent part of the skirt so as to securely grasp that part of the skirt between them and prevent the same from slipping therefrom. This connection between the clamping members and the skirt may be effected in various ways. As shown in the drawings the clamping members have their left ends permanently connected with each 90 other by an eyelet *j* and with the adjacent part of the skirt by a short pliable tab *j'*. The eyelet *j* is preferably oblong whereby the clamping members are prevented from being turned out of place and are compelled to 95 remain parallel or side by side.

The right end of the inner clamping member is permanently connected with the adjacent part of the skirt by a short pliable tab *k* and detachably connected with the corresponding end of the outer clamping member, 100 105

preferably, by a buckle L having a spring pressed tongue or coupling lever l which is pivotally mounted on a plate l' attached to the inner clamping member and passes 5 through one of a plurality of eyes on a plate l'' attached to the outer clamping member.

In adjusting the skirt to the wearer the clamping members are disconnected and the front of the skirt is either let down or raised 10 up between said members the required extent to cause the lower end of the front to be even or horizontally in line with the back after which the outer or front clamping member is coupled at its free end with the inner or rear 15 member and that part of the flap or extension above the clamping members is turned downwardly inside of the skirt, as shown in the drawings. The plaits in the back of the skirt are also let out or taken in the required 20 extent to make the waist band of the skirt fit the waist of the wearer. In effecting the adjustment of the waist band the back fasteners are first removed to free the plaits and then the latter are shifted equal distances so as to 25 retain the placket in the middle after which the back fasteners are again applied.

As the abdomen of the wearer increases in size the front part of the belt at the waist line rises, as shown by dotted lines in Fig. 1, and 30 causes the skirt to raise in front out of its normal position and produce unevenness of the skirt at the bottom. To compensate for this the clamping members are loosened or separated and enough of the surplus flap is 35 drawn out to permit the front of the skirt to resume its normal even position at the bottom after which the clamping members of the belt are again tightened or coupled. As the circumference of the waist increases owing 40 to enlarging of the abdomen the plaits in the back may be let out in the same measure, as shown by dotted lines in Fig. 1. During the period that the form is returning to its normal size, the skirt may be readily adjusted 45 to the then varying conditions as before. These adjustments of the skirt can be effected gradually and easily as the size of the waist varies so that the skirt is comfortable at all times. Furthermore no ripping or basting 50 of the skirt is necessary in changing the same from one size or condition to another.

By constructing the clamping members of comparatively stiff material such as spring steel the same not only hold the reserve part 55 of the flap against being pulled out but the upper front part of the skirt is supported clear of the body, thereby relieving the wearer of the pressure about the waist which is produced by the band or cording of ordinary skirts.

If desired the outer clamping member of the belt may be omitted in which case the flap is simply turned over the inner clamping member and against the inner side of the

skirt, the flap being held in place solely by 65 frictional contact with the adjacent parts of the clothing.

My improved skirt has the additional advantage of being wearable as an ordinary 70 dress skirt after the period of maternity. 70

I claim as my invention:—

1. A skirt having a flap or extension only at the upper end of its front part, and means 75 for holding said flap or extension in various folded positions, substantially as set forth.

2. A skirt having a flap or extension only at the upper end of its front part, and means for holding said flap or extension in various folded positions comprising a belt over which 80 said flap or extension is adapted to be folded, substantially as set forth.

3. A skirt having a flap or extension at the upper end of its front part, and a belt over 85 which said flap or extension is folded and which is connected at its ends to the sides of the skirt while its intermediate part is detached from the skirt, substantially as set forth.

4. A skirt having a flap or extension at the upper end of its front side, and a belt comprising two clamping members between 90 which said flap or extension is arranged, substantially as set forth.

5. A skirt having a flap or extension at the upper end of its front side, and a belt comprising two clamping members between 95 which said flap or extension is arranged, and means for detachably connecting said clamping members, substantially as set forth.

6. A skirt having a flap or extension at the 100 upper end of its front side, and a belt comprising two clamping members between which said flap or extension is arranged, means for permanently connecting the clamping members at one end thereof, and means 105 for detachably connecting the clamping members at the opposite end, substantially as set forth.

7. A skirt having a flap or extension at the upper end of its front side, and a belt comprising inner and outer clamping members 110 which receive said flap or extension between them, said inner member being permanently attached at its opposite ends to said skirt, and said outer clamping member being permanently connected at one end with the inner clamping member and detachably connected at its opposite end with said inner clamping member, substantially as set forth. 115

8. A skirt having a flap or extension at the 120 upper end of its front side, and a belt comprising inner and outer clamping members which receive said flap or extension between them, said inner member being permanently attached at its opposite ends to said skirt, an 125 oblong eyelet connecting one end of the outer clamping member permanently with the corresponding end of the inner clamping mem-

ber, and means for detachably connecting the opposite ends of the clamping members consisting of a spring pressed coupling lever attached to the inner clamping member and 5 an eye plate attached to the outer clamping member and receiving said coupling lever, substantially as set forth.

9. A skirt having a flap or extension only at the upper end of its front part, means for

holding said flap in various folded positions, 10 and means for varying the waist measurement of the skirt, substantially as set forth.

Witness my hand this 1st day of March, 1906:

ROBERT H. PETERS.
